Primary Examiner — Joseph Kukella*Assistant Examiner* — Arva P Adams(74) *Attorney, Agent, or Firm* — Demian K. Jackson; Jackson IPG PLLC(57) **CLAIM**

The ornamental design of a beverage container, as shown and described.

DESCRIPTION

FIG. 1 is a front perspective view of a beverage container according to the invention;

FIG. 2 is a front view thereof;

FIG. 3 is a top view thereof;

FIG. 4 is a bottom view thereof;

FIG. 5 is a rear perspective view thereof;

FIG. 6 is a bottom view of another embodiment of a beverage container according to the invention; and,
 FIG. 7 is a rear perspective view of the beverage container in FIG. 6.

The broken lines show portions of the beverage container that form no part of the claimed design.

1 Claim, 7 Drawing Sheets(56)
